UNITED STATES PATENT OFFICE.

LENNARD L. HAWKINS, OF GREENVILLE, SOUTH CAROLINA, ASSIGNOR OF ONE-HALF
TO CHARLES T. HUGHES, OF GREENVILLE, SOUTH CAROLINA.

LET-OFF MOTION FOR LOOMS.

Application filed October 7, 1922. Serial No. 592,984.

To all whom it may concern:

Be it known that I, LENNARD L. HAWKINS, a citizen of the United States, residing at Greenville, in the county of Greenville and State of South Carolina, have invented certain new and useful Improvements in Let-Off Motions for Looms, of which the following is a specification, reference being had to the accompanying drawings.

10 The purpose of the present invention is to provide a device of this kind for governing the speed with which the yarn lets off from the top or secondary beam or roller to the whip roller.

15 Another purpose is to provide a let-off particularly adapted for use in connection with all constructions of looms, whereas others can only be used on looms involving particular constructions, and cannot, without difficulty, be used on "Draper" looms.

20 A further purpose is to provide an improved let-off motion, which is simple, efficient and practical, not only due to its being capable of use on all constructions of looms, but also due to the fact that it may be manufactured for a relatively low cost.

25 A still further purpose is the provision of a let-off also comprising a friction band brake, for the top or secondary beam or roller, in combination with means to be actuated by the tension on the whip roller of the loom, to lessen the action of the friction band brake against tensioning means, thereby permitting the yarn to freely let off from the top or secondary beam or roller to the whip roller.

30 As soon as the tension on the whip roller decreases, the tensioning means of the friction band brake increases the friction of the band, and thereby lessening the speed with which the yarn lets off from the top or secondary beam or roller. These operations automatically occur, so that the speed with which the yarn lets off from the top or secondary beam is governed with accuracy.

35 It is to be understood that the particulars herein given are illustrative and that while still keeping within the scope of the invention, any desired modifications of detail and

desired proportions may be made in the apparatus according to circumstances. 50

The invention comprises further features and combination of parts, as will be herein-after set forth, shown in the drawings and claimed. 55

In the drawings:—

Figure 1 is a view in perspective of the improved let-off motion as applied to a portion of a loom;

Figure 2 is a vertical section showing the parts in different positions, due to the fact that the friction of the band brake has been lessened on the top or secondary beam or roller;

Figure 3 is an enlarged detail view of the stand 21.

Referring to the drawings, 1 designates the frame of the machine, and 2 designates the top or secondary beam or roller of the loom, from which the yarn lets off during the operation of the loom. This top or secondary beam or roller 2 has a pulley 3 at one end, it being obvious that the pintles or shafts of the top or secondary beam or roller are mounted in bearings of the frame of the loom. A friction band brake 4 engages about the pulley 3 between its annular flanges, and one end of this friction brake band has a reinforced loop 5, which is connected to a bolt 6, which in turn engages through a slot 7 in an upright 8 of the frame of the loom. This bolt is capable of adjustment in the slot, and by means of the nuts 9, the bolt may be held in different positions. 70 75 80

The reinforced loop end of the friction brake band is slotted as shown, and pivotally mounted upon the bolt 6 is a lever 10. This lever engages the slotted portion of the reinforced loop of the friction brake band, so as to hold the lever centrally disposed with respect to the brake band. The lower edge of the lever is provided with V-shaped notches 11. The other end of the friction brake band has a reinforced loop end 12, which is also slotted as shown. A stirrup or link 13 is connected to a transverse pin 14 which engages the reinforced loop of the friction brake band, and the lower end of

the stirrup or link has a slot 15 through which the lever 10 engages, whereby the lower end of the slot 15 may engage in one of the notches 11.

5 An arm 16 is fastened at 17 to a rearwardly inclined portion 18 of the frame, and connected to the lower end of this arm in a notch thereof is a tension coil spring 19, which in turn is connected to the extremity 10 of the lever 10 as at 20. Obviously the spring 19 tensions the lever 10, and thereby holds any one of the notches 11 in engagement with the lower end of the slot 15 of the stirrup or link 13. This construction and 15 arrangement of the aforesaid parts enables the tension upon the friction brake band to be increased or decreased, according to the desired speed with which the yarn is to be let off from the top or secondary beam or 20 roller.

A stand 21 is mounted at 22 and is provided with a slot 23. The end portion of this stand has a laterally extending U-shaped extension 24, which is slotted in its 25 under portion as shown at 25. A suitable whip roller 26 is mounted in suitable bearings in the ends of the stand 21, and over this roller passes the yarn 27 being let off from the top or secondary beam or roller 30. Obviously in letting off the yarn, it tensions on the whip roller 26, and it is the aim of the present invention to govern the speed with which the yarn lets off from the top or secondary beam or roller.

35 A secondary stand 28 is mounted upon a bolt 29, which is adjustably engaged within the slot 23 of the main stand 21.

An equalizing lever 30 is pivotally mounted upon the bolt 31 which is carried by the 40 secondary stand 28, and the upper end of the equalizing lever has a lateral arm 32, which engages under the lever 10. The lower end of the equalizing lever 30 engages in the slot 25 of the lateral U-shaped portion of the 45 stand 21.

Obviously when the yarn in passing from the top or secondary beam or roller tightens, or the tension increases, in passing about the whip roller and then to the drop wire 50 heddle eyes 33, the friction brake band tightens frictionally upon the let-off pulley 3. When this tension increases sufficiently, the whip roller 26 bears upon the lower arm of the equalizing lever 30, causing a pivotal action of the equalizing lever 30, such as will cause the arm 32 to press under the lever 10, raising the lever 10 against the action of the spring 19, and thereby relieving the increased tension or friction on the 55 friction brake band, in which case the yarn will let-off more freely from the top or secondary beam or roller. As soon as this tension of the yarn decreases in passing from the whip roller to the heddle eyes, the pressure of the whip roller on the lower arm of 60

the equalizing lever decreases, allowing the spring 19 to pull upon the lever 10, and thereby increase the friction of the friction brake band on the let-off pulley.

The yarn from the top or secondary beam 70 or roller 2 passes around or beneath the whip roller 26, and thence through the drop wire heddle eyes and hence to the fell (not shown) of the cloth. The top beam or roller 2 carries the let-off pulley 3 about 75 which the friction brake band 4 engages. This friction let-off holds the yarn to the degree of tightness desired. As the yarn tightens in passing over the whip roller 26 it causes downward pressure upon the forward or lower end of the equalizing lever 30, whereupon the upper end thereof exerts upward pressure against the arm 10 against the resistance of the spring 19 and this results in reducing the friction of the band 4 80 upon the pulley 3. This equalizing lever is, as previously stated, supported upon the stand 21, by means of a secondary stand 28. As the pressure from the whip roller 26 is transmitted to the equalizing lever 30, which is pivoted at the center, it causes the upper end to raise the lever 10, thereby slackening the stirrup or link 13, which is attached to the friction brake band 4.

The invention having been set forth, what 95 is claimed is:—

1. A let-off for looms, the combination with the yarn roller and whip roller, of a pulley on one end of the yarn roller, a brake band engaged about the pulley and having 100 one end anchored, a pivoted lever connected with the other end of the band, a tensioned spring applying pressure to said lever for causing the band to grip the pulley, a stand mounted on the frame of the loom and supporting the whip roller, the stand being formed with a slot, an arm pivoted on the stand and having its upper end engaging against the underside of said lever and having its other end extending through said 110 slot and engaging the whip roller.

2. A yarn let-off regulator for looms, the loom including a frame, a yarn roller and a whip roller; comprising a pulley on the 115 yarn roller, a lever pivotally and adjustably mounted on the frame, a friction band encircling said pulley and having one end secured to said pivot and its other end adjustably engaged upon the lever, a spring connected with said lever and the frame for applying tension to the band, a stand mounted on the frame and provided with bearings for the whip roller, said stand being slotted, a support adjustably mounted upon the stand, and a double ended arm pivoted on 120 said support and having one arm engaging beneath the lever and its other arm extending through said slot and engaging the underside of the whip roller.

3. In a loom including a yarn roller and a 130

whip roller, a friction band engaged upon one end of the yarn roller, a spring pressed lever connected with one end of the band for applying tension thereto, a stand carried by the frame of the loom and having bearings for slidably and rotatably supporting the whip roller, the bearings being formed with a slot extending upwardly from

its lower side, and a pivoted arm having 10 its upper end engaging said lever and its lower end extending through said slot and engaging the whip roller.

In testimony whereof I hereunto affix my signature.

LENNARD L. HAWKINS.
